UNITED STATES PATENT OFFICE.

THOMAS P. SHEEHAN, OF NORWICH, CONNECTICUT.

FILLET-WINDING DEVICE.

Application filed November 7, 1921. Serial No. 513,285.

To all whom it may concern:

Be it known that I, THOMAS P. SHEEHAN, a citizen of the United States of America, and a resident of Norwich town, in the county of New London and State of Connecticut, have invented certain new and useful Improvements in Fillet-Winding Devices, of which the following is a specification.

This invention relates to a fillet winding attachment for carding engine cylinders and the like.

An object of the invention is to produce a device that ensures a uniform stretch and tension to the fillet while being wound, which may be regulated to suit the kind of fillet to be used, or the necessities of the occasion.

A further object is to produce an attachment that is equally serviceable in winding fillet upon the smaller cylinders of a card, such as the doffer, worker, dirt and others, as well as upon the large cylinder or swift.

A still further object being to reduce the number of attendants required to wind fillet upon the smaller cylinders by so arranging the device that it may be operated by one attendant in place of three heretofore necessary for this operation.

Another object being the production of a device that is compact and so arranged as to be readily placed for operation adjacent a card for the purpose of winding a swift or it may be temporarily attached to the card frame if desired.

Heretofore the process of winding the smaller cylinders has been a crude one, involving the services of at least three attendants, two of whom laboriously turned the cylinder by hand, while the third guided the fillet thereon.

It will be readily understood that under those conditions it was impossible to maintain a uniform stretch and tension to the fillet, and also required the labor of two attendants which is dispensed with in the present invention.

In the winding of a swift it has been customary to rotate it by hand during the operation, and if preferred the same method may be employed in the present instance, but, with the improved tension regulating devices herein employed it is practical to power drive the said swift at a speed consistent with good winding results and thus eliminate the services of at least one attendant and at times two.

As it is an object of this invention to pro-

duce an attachment that is capable of operation in connection with, or independently of, the card proper, power driving devices are preferably made a part thereof, which will be brought into play in some instances and allowed to remain idle or temporarily eliminated in others.

It is believed that a device of this description having the capabilities thereof is new in the art, and therefore it is not the intention to limit the invention to the precise construction and arrangement shown, as it is obvious that various slight changes might be made without departing from the spirit and scope thereof.

The invention further consists in certain novel features of construction and arrangement of parts which will be fully understood from a description of the drawings and the claims hereinafter given.

Of the drawings:

Figure 1 represents a side elevation of the attachment as it would appear for use in winding a swift.

Figure 2 a view looking in the direction of arrow A, Figure 1, the drive mechanism not being shown therein.

Figure 3 a view similar to Figure 1 on a smaller scale showing the device in place adjacent a card for the swift winding operation.

Figure 4 represents a section of fillet in side elevation.

Figure 5 a view similar to Figure 1 showing the device as it may be used for winding fillet on one of the smaller cylinders of a card.

Figure 6 a view of the power drive mechanism looking toward the left Figure 5.

Figure 7 a view of a swift partially wound with fillet.

Like characters designate like parts throughout the several figures of the drawings.

Referring to the drawings:

It is an object of this invention to produce a device that is compact and serviceable, which is capable of regulating the stretch and tension of fillet, and facilitating in the winding thereof on a swift, as well as performing the above functions and actually winding the fillet on the other small cylinders of a card at different times. In other words, the invention contemplates the use of one device or machine for the winding of fillet on the largest cylinder of a card com-

monly called the swift; and the winding of fillet on the smaller cylinders of the card with but slight change in the normal arrangement or use of some of the parts.

5 For instance, Figure 3 of the drawings shows the attachment positioned adjacent a card 10 having two swifts 11 and 12, said attachment being so adjusted as to permit fillet winding on the swift 12. This view is somewhat diagrammatic, but it will be understood that for this operation the majority of the smaller cylinders coacting with the swifts will be removed from the engine in order that access may be had thereto.

10 15 In this application of the device the winding mechanism forming part thereof will not be called into use, but when winding fillet on the smaller cylinders (see Figure 5) the said winding mechanism performs a very important feature of the invention.

15 Figures 2 and 3 show the use of a friction beam when winding fillet on a swift which may or not be used when winding fillet on the smaller cylinders.

20 25 In fact, it may be desirable to use a rotatable drum, in the latter instance, which has friction applied thereto by means of a brake strap and weight.

30 35 Any other changes of arrangement or use of the parts for the two uses of the device above referred to are very slight and will be referred to in the course of the following description.

Primarily this device was designed to 35 produce results in fillet winding not heretofore attained by the crude apparatus used. This meant that the fillet must be uniformly stretched throughout its length before being applied to the cylinder and 40 during the operation of winding an even uniform tension must be maintained.

45 The present invention has attained these results even though the mechanism used is of a simple arrangement.

50 55 For convenience the device will be first described as for use in winding a swift and thereafter for use in winding one of the smaller cylinders of a card, but it will be understood that the order of description does not necessarily imply the order of importance of the invention as it is considered of equal value for either purpose.

Figures 1 and 2 show a floor stand 15 to which an upright 16 is securely bolted and 55 a similar upright 17 adjustably secured for the purpose of accommodating various lengths of cylinders to be wound. Both of these uprights have adjustably secured thereto L shaped side frames 18 and 19, the 60 overhanging portions thereof 20 and 21 being in turn supported by the adjustable extensions 22 and 23 of the uprights 24 and 25.

The said uprights 16 and 17 at the top ends thereof are provided with receptacles 65 26 for the squared ends of a rod 27 sup-

porting a preferably non-revolvble cone shaped beam 28 to be further described. The said rod being held in the said receptacles by means of the pins 29.

In practice the fillet F is wound around the beam 28 two or more times as occasion requires, and is led over a rod or whip roll 30 supported by bell cranks 31 pivoted on the rod 32 suitably journaled in the side frames 18 and 19. Both rods 30 and 32 are preferably loose in said bell cranks and side frames respectively being held from longitudinal movement by the use of collars 33 and 34, 35 and 36, see Figure 2. The rod 32 while serving as a pivot for the bell cranks also serves as a tie rod for the said side frames. The several collars being set screwed to the rods which are of such length as to accommodate adjustment of the upright 17 and side frame 19 to the longest cylinder to be wound.

Both the bell cranks are under the control of springs 37 which may be adjusted as to tension by means of the bolt 38 and nut 39.

The uprights 24 and 25 are mounted on a floor stand 40 similar to 15 and while said stands are shown as separate members it is obvious that they might be made in one if desired, and trucks attached to facilitate in moving about the mill.

The extension 22 is provided with a bracket 41 adapted to support one end of a drive shaft 42 on which a clutch pulley 43 is loosely mounted and adapted to drive said shaft upon movement of the clutch actuator 44. Movement of the actuator is accomplished by depressing the treadle 45 pivoted at 46, against the action of spring 47, said treadle having a link connection with the bell crank 48 which is forked at its upper end and adapted to engage said actuator 44.

The particular form of clutch shown is a convenient one, but any design of clutch that may be operated by foot or manually might be used.

The shaft 42 has fast thereon a pinion 50 which will be further described.

The clutch drive mechanism just described will not be called into play when the device is in use to wind fillet on a swift, as at that time the swift may be turned by hand, by means of the levers 51 temporarily fast on the shaft 52 of the swift, or by the usual pulley and belt means at a slow speed.

As previously explained the fillet is wrapped around the beam 28 and led over the slack taking rod 30 to the swift 12 or to the swift 11 as the case may be.

The side frames 18 and 19 are made adjustable so as to properly lead the fillet F over the first swift, without contact therewith, to be wound on the second swift.

If desired the device may be secured to the engine frame by removing the floor stand 40 and the uprights carried thereby and thereafter bolting the side frames at 5 the overhanging portion thereof to the engine frame.

To wind fillet on the swift an end is first secured thereto and thereafter for the first few wraps the swift is preferably turned 10 by hand or until the proper wrap is obtained at which time slow power drive may be applied as previously explained. The friction caused by the fillet being wrapped around the beam 28, which may be regulated 15 by the number of wraps, stretches the fillet uniformly upon movement of the swift, and any tendency of variance of tension of the fillet will be cared for by the spring controlled rod 30.

20 By the use of this device the service of one attendant may be dispensed with, as one may guide the fillet on the swift, and another stand by the power control for the purpose of starting and stopping the swift.

25 The beam 28 as shown is conical, the large end being at the right, see Figure 2, which is the direction of wind of the fillet on the swift. As the wind advances on the swift, the several wraps of the fillet on the beam will advance towards the large end of the beam but always a little behind the wraps on the swift and never ahead of it. This ensures the fillet of easy guidance and the laying of each wrap snugly against the 35 preceding one with but slight effort on the part of the attendant or undue stretch of the fillet.

While the beam 28 is herein shown as a 40 stationary one, it is obvious that it may be a rotary one having a brake band and weight attachment to add friction thereto as shown in Figure 5 of the drawings.

45 For winding fillet on the smaller cylinders of the card, the device may be placed in any suitable spot adjacent the card or otherwise, but in this instance the attached drive mechanism previously described will be brought into play.

A cylinder 55 having the usual shaft 56 50 will have placed thereon a gear 57 to which is also fast a ratchet 58 both being temporarily fast upon the said shaft 56 by any suitable means such as a set screw 59. The cylinder will be placed so that its shaft will 55 rest in bearings 60 with the gear 59 in mesh with the pinion 50, when the pawl 61 will be turned to engage the ratchet 58.

At this time it is preferred to use a 60 rotary drum or beam 62, which may or may not be conical in shape, and which has a brake band 63 held snugly around a brake drum 64 by means of a weight 65, which may be varied to suit the occasion. The fillet will be led from any source of supply 65 and wrapped the desired number of times

around the beam 62 and led over the rod 30 and its end will be firmly secured to the cylinder 55. The drive mechanism may now be operated intermittently until such time as the fillet has been properly started 70 on the cylinder and thereafter run continually until the winding is complete, whereupon the fillet is cut and the end secured on the cylinder as usual. Preferably the drive is operated at a speed that allows careful 75 guiding of the fillet by the attendant and not as might be thought at a high rate.

By the use of this device an even stretch and tension is given to the fillet, and cylinder winding may be accomplished by one 80 attendant in place of two heretofore required.

If so desired the fillet may be cut the length required for a small cylinder and wrapped around the beam 62, the end last to leave being held in a clamp attached to a strap, which is to be of sufficient length to allow the said end to reach the cylinder at the completion of winding. The end may then be secured while under tension as before. 85

Having described the invention I claim:

1. In a fillet winder of the class described, a portable frame; a stationary friction beam supported on said frame adapted to be encircled by the fillet on its way to be wound; a whip roll also supported on said frame; bearings on said frame adapted to receive a cylinder to be wound; and drive means supported by said frame under the control 95 of the operator. 100

2. In a fillet winder of the class described, a portable frame; a stationary friction beam supported by said frame adapted to be encircled by the fillet on its way to be wound; a whip roll also supported by said frame; bearings on said frame adapted to receive a cylinder to be wound; drive means supported by said frame under the control 105 of the operator; and means to appreciably 110 vary the distance between said beam and said whip roll.

3. In a fillet winder of the class described, a portable frame capable of adjustment for height; a stationary friction beam supported by said frame and adapted to be encircled by the fillet on its way to be wound; a drive means supported by said frame; and a whip roll intermediate said beam and 115 said drive means. 120

4. In a fillet winder of the class described, a portable frame capable of adjustment for height; a conical friction beam supported by said frame; a drive means supported by said frame; and a tension equalizer intermediate said beam and said drive means. 125

5. In a fillet winder of the class described; a portable frame adapted to be adjusted as to width; a conical friction beam supported by said frame; a drive means supported by 130

said frame; and a whip roll intermediate said beam and said drive means.

6. In a fillet winder of the class described, a portable frame adapted to be adjusted as to height and width; a stationary conical friction beam supported on said frame; a spring controlled whip roll supported on said frame; bearings on said frame adapted

to receive a cylinder to be wound; a drive means supported by said frame adapted to 10 actuate said cylinder when so placed; and a tension equalizer intermediate said beam and said drive means.

Signed by me at Boston, Mass., this 1st day of November, 1921.

THOMAS P. SHEEHAN.
